ROTARY INTERNAL COMBUSTION ENGINE

Enrique Shufeldt, La Cueva, N. Mex.

Application July 11, 1940, Serial No. 344,974

1 Claim. (Cl. 123—11)

This invention relates to rotary internal combustion engines and has for an object to provide a simplified engine which will be devoid of valves, which will have four power impulses to each revolution of the shaft and which will simultaneously exhaust the burned gas, draw in fresh gas and compress the charge during the power impulse.

A further object is to provide an engine having impeller blades travelling in a planetary path around a globular portion of the shaft and having respective pins engaged in segmental grooves ninety degrees apart in the globular portion, the pins travelling at an angle to the direction of the grooves and having reciprocatory motion from end to end of respective grooves to impart rotary motion to the shaft.

A further object is to provide apparatus of this character which will be formed of a few strong, simple and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawings forming part of this specification:

Figure 1 is a front elevation of a rotary internal combustion engine constructed in accordance with the invention.

Figure 2 is a plan view of the engine with the top of the impeller removed to expose the impeller rings and blades of the globular portion of the shaft.

Figure 3 is a perspective view showing the two independently movable impeller rings separated from each other.

Figure 4 is a perspective view showing the shaft, grooved globular driving portion of the shaft, impeller rings and blades assembled with the globular portion of the shaft.

Figure 5 is a longitudinal sectional view of the invention taken on the line 5—5 of Figure 2.

Figure 6 is a plan view similar to Figure 2 but showing the impeller blades in a different position of their relative movement.

Figure 7 is a front elevation of one of the rings and its blades.

Figure 8 is a diagrammatic view showing the intake position of the blades.

Figure 9 is a diagrammatic view showing the compression position of the blades.

Figure 10 is a diagrammatic view showing the power position of the blades.

Figure 11 is a diagrammatic view showing the exhaust position of the blades.

Referring now to the drawings in which like characters of reference designate similar parts in the various views, the engine comprises a globular casing 10 having an annular housing 11 arranged in surrounding relation to the casing. A pair of shaft bearings 12 extend in aligned position from the casing 10 and the housing 11 is inclined relatively to the bearings in a plane intersecting the axis of the bearings and the casing 10 at approximately 30°, as best shown in Figure 1. The housing is formed of two sections connected together by bolts 13, one of the bearings 12, the upper section of the housing, and the upper part of the casing are formed as a unit. Also the lower section of the housing, the lower part of the casing and the other bearing are formed as a unit.

Rotatably mounted in the casing is a hollow metal ball 14, shown best in Figure 4, having 20 sockets 15, best shown in Figure 5, to receive the squared ends of aligned sections of the engine shaft 16. The sections of the shaft extend through the bearings 12 and the latter may be mounted on any type of a support desired.

25 The metal ball 14 forms a globular portion of the engine shaft 16 and nicely fits within the globular housing 10. The globular portion 14 of the shaft is provided in the present embodiment of the invention with four segmental grooves 17, 30 18, 19 and 20, best shown in Figure 4. The grooves are arranged at an angular advance of 90° from each other and terminate short of the shaft 16 at what may be termed the poles of the globular portion 14 at its connection with the shaft.

35 Impeller rings 21 and 22, best shown in separated condition in Figure 3, are disposed in superposed axially aligned position to ride one upon the other at different speeds. The ring 21 is provided with diametrically oppositely disposed impeller blades 23 which are offset as shown at 24 in Figure 7 to receive the companion ring 22 while the latter is provided at diametrically opposite points with impeller blades 25 which are offset as shown at 26 in Figure 3 to receive 40 the impeller ring 21. Thus the blades of one ring overlap the other ring and the blades of both rings are of such contour as to snugly fit in the housing 11, which latter is analogous to the cylinder of an engine.

50 The housing 11 is provided with an exhaust pipe 27, best shown in Figure 2, and is also provided with an intake pipe 28, these pipes entering the housing 11 on opposite sides of a vertical plane passing through the axis of the shaft 16.

55 The intake pipe is connected to a carburetor 29, as best shown in Figure 1.

The impeller ring 21 is provided with pins 30 and 31, best shown in Figure 3, projecting interiorly of the ring at the impeller blades 23. Likewise, the impeller ring 22 is provided with pins

32 and 33 which project interiorly of the ring at the blades 25. The pins of the ring 21 are offset as shown at 34 in Figure 3 while the pins of the ring 22 are offset as shown at 35. These offsets permit the pins and blades to oscillate in the same plane, while the rings oscillate in parallel planes symmetrical to the plane of the pins and piston blades at different speeds to turn the shaft as will now be described.

As clearly shown in Figure 4 the pins 30 and 31 of the impeller ring 21 ride respectively in the diametrically disposed grooves 17 and 18 of the globular portion 14 of the shaft. The pins 32 and 33 of the impeller ring 22 ride respectively in the diametrically opposite grooves 19 and 20 of the globular portion of the shaft.

The power stroke of ignited gas causes the pins to travel in the housing 11 at an angle to the direction of the grooves from end to end of respective grooves and since the pins travel in an inclined planetary course they force the shaft to rotate axially. The rings oscillate on each other as the pins travel from end to end of their respective grooves in order to compensate for the difference in the speed of the rings at any given moment initiated by movement of their impeller blades.

There are four power impulses to each cycle, the compressed gas being fired by a spark plug 36 connected by a wire 37 to a magneto 38 which is mounted on one of the bearings 12 and is geared to the fly-wheel section 16 of the shaft as shown at 39 in Figure 1.

In the diagrammatic Figures 8, 9, 10 and 11, for the purpose of more clearly explaining the operation, the two blades 25 of one ring have been distinguished by priming one blade, and also the two blades 23 of the other ring have been distinguished by priming one of the blades.

Figure 8 shows fresh gas being drawn into the housing between the blade 23' and the blade 25, while gas is being compressed between the blade 25 and the blade 23.

Figure 9 shows the compressed gas between the blades 25 and 23 being fired, while the fresh gas supply between the blades 23' and 25 is ready to be compressed since the blade 23' is travelling faster than the blade 25.

As shown in Figure 10, the ignited gas between the blade 25 and blade 23 is shown furnishing the power stroke since the blade 23 is moving faster than the blade 25. At the same time, the blade 23' is moving faster than the blade 25 and is compressing the charge which is shown ready to be compressed in Figure 9. At the same time, since the blade 23' is moving faster than the blade 25', a fresh charge is being drawn into the housing between the blades 23' and 25.

As shown in Figure 11, the spent gas after furnishing the power stroke and driving the blades 23 and 23' faster than the blades 25 and 25', is about to be expelled from the casing, while at the same time a compressed charge is ready to be fired between the blades 23' and 25 and a fresh charge ready for compression exists in the housing between blades 23' and 25'. During exhaust of the spent gases, the compressed charge is fired to initiate the next succeeding cycle course around the globular portion 14 of the shaft. The respective pin first travels diagonally downward in its groove during this planetary course and the pin will force the shaft to rotate axially through the

initial angular advance of 180° during the time period the blade moves from left to right in the annular housing, then the pin reaches the end of its groove and reverses its direction to guide the 5 blade from right to left diagonally upward in the annular housing to turn the globular portion of the shaft through the second 180° angular advance. The impeller rings oscillate upon each other at varying speeds during a complete cycle of the globular portion of the shaft. The variation of oscillatory speed of both impeller rings and consequently the relative variation of the speed of the respective blades of the rings produce the power, exhaust, intake and compression 10 positions of the blades and is caused by the positions of the blades and is caused by the grooves being close together at the poles of the globular portion of the shaft and wide apart at the central circumference, or equator as it may be termed, of the globular portion of the shaft. 15 From the above description it is thought that the construction and operation of the invention will be fully understood without further explanation.

What is claimed is:

An engine including a globular casing, an annular housing arranged in surrounding relation on the casing, a pair of aligned shaft bearings extending from the casing and the housing, the housing being inclined relatively to the axis of the bearings at an angle, a shaft having cylindrical portions disposed in said bearings and having a globular intermediate portion disposed in said casing and housing, said globular portion being provided with segmental grooves spaced uniformly from each other at the central circumference of the globular portion and converging toward and terminating short of the poles at the junction of the globular portion with the cylindrical portions of the shaft, a pair of axially aligned impeller rings superposed upon each other in surrounding relation on said globular portion, impeller blades disposed at diametrically opposite points of each ring fitting in the housing, pins projecting radially inward from each ring at the blades of the ring slidably engaged in respective grooves of the globular portion, exhaust and fuel inlet pipes connected to said housing on opposite sides of one cylindrical portion of the shaft, a spark plug connected to the housing at a point substantially diametrically opposite a point midway between the intake and exhaust pipes, and means for energizing the spark plug, the arrangement being such that each explosion starts one of the blades downward in the annular housing on a planetary course around the globular portion of the shaft, the respective pin of said blade first travelling in its respective groove to force the shaft to rotate axially through an initial angular advance of 180° then reversing its direction in the groove to force the shaft through the second 180° angular advance, the impeller rings oscillating upon each other during each complete cycle of the globular portion at respectively different speeds due to the grooves being close together at the poles of the globular portion and wide apart at the central circumference of the globular portion of the shaft to cause the blades to assume power, exhaust, intake and compression positions during each revolution of the globular portion of the shaft.

ENRIQUE SHUFELDT.
